DESIGN FOR A HANDKERCHIEF OR SIMILAR ARTICLE

Lester L. Mendelson, New York, N. Y.

Application August 7, 1937, Serial No. 70,911

Term of patent 3½ years

To all whom it may concern:

Be it known that I, Lester L. Mendelson, a citizen of the United States of America, and resident of the city, county, and State of New York, have invented a new, original, and ornamental Design for a Handkerchief or Similar Article, of which the following is a specification, reference being had to the accompanying drawing, forming part thereof.

The figure is a plan view of a handkerchief or similar article, showing my new design.

I claim:

The ornamental design for a handkerchief or similar article, as shown.

LESTER L. MENDELSON.
